CAT PERCH AND SCRATCHING POST

William C. Whitlock, 220 12th Ave.,
Holdrege, Nebr. 68949

Filed July 13, 1973, Ser. No. 378,876

Term of patent 14 years

Int. Cl. D30—07

U.S. Cl. D30—42

FIG. 1

FIG. 2

FIG. 1 is a perspective view of a cat perch and scratching post showing my new design; and

FIG. 2 is a fragmentary elevational view illustrating the upper terminal points of the inclined support members.

I claim:

The ornamental design for a cat perch and scratching post, as shown and described.
